(57) **CLAIM**

The ornamental design for a closed circuit television camera,
as shown and described.

DESCRIPTION

FIG. 1 is a front and left side perspective view of a closed circuit television camera showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a right side elevational view thereof, showing the closed circuit television camera being supported by a fixed structure when used. The fixed support structure is shown to illustrate an environment only and forms no part of the claimed design.

The broken lines in FIG. 8 are for illustrative purpose only and form no part of the claimed design.
